UNITED STATES PATENT OFFICE.

CARL ICKES, OF CHICAGO, ILLINOIS.

GREENHOUSE-GUTTER.

1,244,500.

Specification of Letters Patent. Patented Oct. 30, 1917.

Application filed February 9, 1917. Serial No. 147,667.

To all whom it may concern:

Be it known that I, CARL ICKES, a citizen of the United States, residing at Chicago, in the county of Cook and State of Illinois, 5 have invented a certain new and useful Improvement in Greenhouse-Gutters, of which the following is a specification.

My invention relates to green houses and especially the gutters thereof. It will be understood by those skilled in the art that green houses usually consist of a number of sections or individual buildings joined together at the eaves so as to make a single structure. With green houses of this type 15 the water resulting from rain and snow cannot fall to the ground as soon as it reaches the eaves but must be carried along to the end of the building. Green houses are of comparatively light construction and yet 20 it is of great importance that the water should be carried off effectually and not be permitted to leak at the point where the buildings are joined. To produce a water tight gutter at the eaves has always presented 25 considerable difficulty, especially where wood is employed in the construction of the trough or gutter. Metal gutters are frequently employed but they are objectionable in some respects, particularly because they 30 are ready conductors of heat, and in winter transmit the heat of the green house to the atmosphere and thus dissipate it at a much greater rate than wood would do, while in summer they absorb heat from the sun and 35 transmit it to the inside of the green house, thus unduly raising the temperature within. For this and other reasons wood is preferable, but even cypress has a certain co-efficient of expansion and contraction under 40 variations in moisture, and the object of my invention is to produce a construction employing wood which will nevertheless 45 remain water-tight under all conditions and weathers and which will possess a configuration which may be readily produced commercially and which will allow for certain irregularities of manufacture so that the parts will be sure to assemble even though not made with perfect accuracy.

50 I attain my object by the construction illustrated in the accompanying drawings, in which:

Figure 1 shows in a more or less conventional form a cross sectional elevation of a 55 green house employing my invention.

Fig. 2 is a cross sectional elevation of

a green house gutter embodying my invention.

Fig. 3 is a fragmentary detail showing on an enlarged scale the contour of the 60 parts where the side member of the gutter joins the bottom.

Similar numerals refer to similar parts throughout the several views.

The posts 1 support the roof structure 65 according to any suitable plan. The plans may be varied and various ones are well known and hence need not be here described in detail. It will be sufficient for the present purpose to say that the rafters 2, which 70 form part of the roof structure, are overlaid with glass tops 3 as usual. At the foot of the rafters are members 4 which form the sides of the trough or gutter. In order to carry off the moisture collecting inside of 75 the roof it is desirable to provide drip conductors 5 of any suitable type. These are here shown to be fastened to the insides of the side members 4.

Extending from one side member to the 80 other is a bottom member 6 which has grooves 7 in its upper surface arranged parallel and near to the edges. Each groove is preferably inclined at both sides. The side members 4 are each rabbeted at point 85 8 to receive the edge of the bottom member, consequently the side member projects for a limited distance over the top of the bottom member. A tongue 9 is formed at the 90 top of the rabbet and this fits into the groove formed in the bottom member. By preference the tongue fills the entire bottom of the groove, but the external wall of the side member is vertical and does not follow the inclined side of the groove, hence a channel 95 10 is formed which is widest at the top and has converging sides which meet at the bottom.

One of the primary advantages of the 100 structure previously described and particularly the herein set forth relation of the groove 7, tongue 9 and vertical inner face of the side 4 flows from results produced thereby in the process of painting the structure. As the paint is applied to the vertical inner face 105 of the side 4 a portion thereof will flow downward and settle in the channel 10 and thus automatically provide a water-proof filler to prevent water from gaining access to the joint, thereby obviating undesirable swelling and shrinkage of the wood and maintaining the joint tight at all times. The ad- 110

vantage thus gained is entirely involuntary in that the paint automatically settles in the channel. Therefore, the painter does not have to make a conscious effort to put 5 paint in the channel and hence no skilled labor is required to completely erect the gutter, while the necessity and expense of providing an independent water-proof filler is entirely avoided.

10 Another feature of great practical importance in respect to the invention is that the shape of the bottom and sides is so simple that these parts can be easily produced commercially; that is to say, they lend 15 themselves readily to milling and do not have to be manufactured by hand; nor will the gutter fail to assemble if the expected inaccuracies of manufacture in quantity present themselves.

20 Having thus described my invention, what I claim as new and desire to secure by Letters Patent, is:

25 1. A green house gutter having a bottom and a side rising from it, the bottom member having a groove in its upper surface arranged parallel with the edge of said bottom member, and the side member projecting over the edge of the bottom member and having a tongue descending into said 30 groove, said groove having an inclined inner side whereby a channel is formed between it and the adjacent upright surface of the side member.

Copies of this patent may be obtained for five cents each, by addressing the "Commissioner of Patents, Washington, D. C."

2. A green house gutter having a bottom member arranged flatwise and having a flaring groove in the top running along near the edge, and a side member rising at the edge of the bottom member, said side member having a tongue projecting over into said groove and completely filling the bottom 40 thereof, the side member having a vertical side surface rising from the far edge of the bottom of the groove.

3. A green house gutter having a side member having a rabbet in one side and a depending tongue on the overhanging portion, and a bottom member the edge whereof enters said rabbet from the side, said bottom member having a groove in its top surface, into which said tongue fits, the side member 50 having a vertical surface on the gutter side and the gutter side of the groove being inclined away from said vertical surface for the purpose described.

4. A green house gutter having a bottom 55 and a side rising therefrom, said bottom having a groove in the top running parallel with the edge, and the side member projecting over the top of the bottom member, and having a tongue descending into said groove, 60 a portion of said groove being left unoccupied by said tongue.

In witness whereof, I have hereunto subscribed my name.

CARL ICKES.
